UNITED STATES PATENT OFFICE.

FREDRICK W. NITTEL, OF ATTLEBORO FALLS, MASSACHUSETTS, ASSIGNOR TO M S COMPANY, OF ATTLEBORO, MASSACHUSETTS.

WATCH-BRACELET END HOOK.

Application filed March 17, 1926. Serial No. 95,367.

This invention relates to certain new and useful improvements in watch bracelet end hooks, and the primary object thereof is to provide a simplified form of hook of this type which can be easily and quickly assembled and consequently more economically produced.

The invention further aims to provide a hook of this character which can be easily and quickly operated and which is positive in its holding action.

In the drawings:

Figure 1 is a bottom plan view of the invention,

15 Figure 2 is a section on line 2—2 of Fig. 1 and

Figure 3 is a similar view on line 3—3 of Fig. 1.

In proceeding in accordance with the present invention, a main casing is employed which is made of a blank that has a body 1 formed at one end with a hook 2 and at its opposite end with an end wing 3, the sides of the body being formed with side 25 wings 4.

The latch structure is provided for holding the usual bail L of the watch in the hook, and which comprises a casing formed of a blank having a body 5, which like the casing, has an end hook 6 an end wing 7 and side wings 8.

The latch consists of a block of metal 9 having a nose 10 at one end to engage the watch bail and having an opening 11 at its 35 opposite to receive a coil spring 12.

In assembly the latch is placed in its casing the end wing 7 being bent to engage the coil spring and the side wings 8 being bent over to engage the latch sides so as 40 to provide guides wherein the latch may slide. The latch casing thus assembled is then placed in the main casing, whereupon the hook of the latter is bent about the hook of the latch casing and the wings of the 45 main casing are bent over onto the respec-

tive wings of the latch casing. The parts are thus united without the use of solder and due to the fact that the structure is formed of two nested casings a double wall thickness is provided which has increased 50 strength accordingly.

Having thus described my invention what I claim as new and desire to secure by Letters Patent is:—

1. In a hook of the type set forth, a main 55 casing having a hook at one end and a wing at its opposite end and having side wings, a latch structure having a casing formed with a hook at one end, and a wing at its opposite end and having side wings, a latch block having a nose at one end and having an opening at its opposite end, and a coil spring in the opening, the side wings of the latch casing being bent over to engage the block so as to slidably guide same and the end wing being engaged with the spring, the latch casing being nested in the main casing and the hook and wings of the latter being bent to engage over the respective hook and wings of the latch casing thereby 65 70 to secure the latter within the main casing.

2. In a hook of the type set forth, a main 75 casing having a hook at one end and a wing at its opposite end and having side wings, a latch structure having a casing formed with a hook at one end, and a wing at its opposite end and having side wings, a spring pressed latch in the latch casing, the side wings of the latch casing being bent to 80 engage over the latch to slidably engage same, the end wing of the latch casing being engaged with the spring, the latch casing being nested in the main casing and the wings and hook of the latter being bent 85 to engage the respective wings and hook of the latch casing.

In testimony whereof I have signed my name to this specification.

FREDRICK W. NITTEL.
